UNITED STATES PATENT OFFICE.

OLIVER P. MEGAHAN, OF WESTERVILLE, OHIO.

RAILROAD-TIE.

1,119,853.

Specification of Letters Patent.

Patented Dec. 8, 1914.

Application filed March 10, 1913. Serial No. 753,467.

To all whom it may concern:

Be it known that I, OLIVER P. MEGAHAN, a citizen of the United States, residing at Westerville, in the county of Franklin and State of Ohio, have invented a certain new and useful Improvement in Railroad-Ties, of which the following is a specification.

This invention relates more especially to railroad ties of metal and has for its object to provide an article of the kind that is strong and durable in construction and at the same time provides ample resilience. Heretofore it has been found difficult to provide suitable resilience in ties of material other than wood.

The invention is embodied in the construction herein illustrated and described, the features of novelty being pointed out in the claims.

In the accompanying drawings—Figure 1 is a view in side elevation on one end of the tie, a rail being shown in section in position thereon. Fig. 2 is a cross section on the line $x-x$ looking to the right. Fig. 3 is a detail in isometric perspective of a bridge piece used in the construction. Fig. 4 is a similar view of the cushion. Fig. 5 is a plan view of one end of the tie with a rail thereon. Fig. 6 is a detail in isometric perspective of the tie body. Fig. 7 is a detail illustrating one of the clips or fastening devices for holding the rail. Fig. 8 is a modification of the cushioning member.

The body of the tie is formed out of a strip of flat metal cut on one edge at four points and then bent transversely to form a box-like structure having a vertical wall 10 and lateral and end horizontal flanges 11 and 12 respectively. These horizontal flanges afford an extensive and therefore firm bearing on the ballasting or road bed. Secured at each end of the tie body by means of rivets 13 is a pair of standards 14, bent to form shoulders 14^a to rest on the upper edge of the wall 10 and to form outwardly and oppositely extending horizontal supports 14^b. Resting on the supports 14^b are the ends of a bridge 15 depressed at its middle to U-form to receive a cushion 16.

The cushion 16 consists of a short piece of 50 stiff metal bent to tube or C-form. The depressed portion of the bridge is cut at each end to form tongues 15^a that are bent up to form stops to prevent the escape of the cushion when in place under the rail, which 55 is designated 17.

The rail 17 is secured on the bridge by means of stiff bent spring clips 18 and threaded bolts 19 securing them to the standards. The spring 18 is secured on the 60 shank below the head of the bolt by means of a square key 20 set in a transverse notch 19^a cut in one side of the bolt shank, and the threaded end of the bolt passed down through a hole, such as seen at 15^b, Fig. 3, 65 in both the bridge and support of the standard.

The bolt is secured in place by means of a nut 21 supplemented by a suitable jamming or locking member 22. If the shank 70 of the bolt be made square in cross section and all the holes through which it extends be made to fit as indicated the springs 18 will be prevented from turning horizontally. A single key 20 can be made to do duty for 75 a pair of the clips. The spring clips 18 are strong but elastic members and they are so made as to yieldingly take slight lateral tiltings or spreadings of the rails without permanent injury to or dislocation of the 80 rail securing means.

In Fig. 8 is illustrated another form of the cushion used on the bridge. It consists of two of the short open tubes, one smaller than the other, nested together in reverse 85 position. When so made the tubes can be of thinner metal.

What I claim is—

1. In a railroad tie, the combination with a body having a rail support thereon, of a 90 spring clip to resiliently engage the base of the rail and a bolt with means on the bolt for holding the clip yieldingly in a state of tension independently of the rail support.

2. In a railroad tie, the combination with 95 a body having a rail support thereon, of a spring clip to embrace the base of the rail, and a bolt with means on the bolt for hold-

ing the clip in a state of tension independently of the rail support, said bolt constructed to engage the clip and rail support to prevent the turning of the clip.

5 3. In a railroad tie, the combination with a body having a rail support thereon, a spring clip to embrace the base of the rail, and a bolt passed through the spring clip,

and a key in the bolt adapted to hold the clip in a state of tension on the bolt independently of the rail support.

OLIVER P. MEGAHAN.
